UNITED STATES PATENT OFFICE

123,758

DESIGN FOR A FLOOR LAMP

Frederick J. S. Gay, Lahaina, Territory of Hawaii

Application January 11, 1940, Serial No. 89,397

Term of patent 14 years

To all whom it may concern:

Be it known that I, Frederick J. S. Gay, a citizen of the United States of America, residing at Lahaina, Maui, Territory of Hawaii, have invented a new, original, and ornamental Design for a Floor Lamp, of which the following is a specification, reference being had to the accompanying drawing, wherein the figure is a perspective view of a floor lamp, showing my new design.

I claim:

The ornamental design for a floor lamp, as shown.

FREDERICK J. S. GAY.
